Primary Examiner — Christian P. McLean(74) *Attorney, Agent, or Firm* — Leason Ellis LLP(57) **CLAIM**

The ornamental design for a lopper as shown and described.

DESCRIPTION

FIG. 1 is a left-side perspective view of a lopper according to our new design;

FIG. 2 is right-side perspective view thereof;

FIG. 3 is a front elevation view thereof;

FIG. 4 is a right-side elevation view thereof;

FIG. 5 is a left-side elevation view thereof; and,

FIG. 6 is a top plan view thereof.

The broken lines showing portions of the lopper are included for the purpose of illustrating environmental structure and form no part of the claimed design.

The dot-dash broken lines shown in all figures immediately adjacent to the claimed areas represent the boundaries of the design and form no part thereof.
